(57) **CLAIM**

The ornamental design for an air cleaner of a truck vehicle, as shown and described.

DESCRIPTION

FIG. 1 is a left, front perspective view of an air cleaner of a truck vehicle showing our new design;

FIG. 2 is a left side elevation view thereof;

FIG. 3 is a bottom plan view thereof;

FIG. 4 is a top plan view thereof;

FIG. 5 is a front elevation view thereof;

FIG. 6 is a rear elevation view thereof; and,

FIG. 7 is a right side elevation view thereof.

The broken lines depict portions of the air cleaner that form no part of the claimed design.
